DESIGN FOR A CENTER BAR FOR OPHTHALMIC MOUNTINGS

Louis Harry Budd, Malden, Mass., assignor to
Chaffin Optical Company, Inc., Boston, Mass.,
a corporation of Massachusetts

Application January 10, 1934, Serial No. 50,363

Term of patent 7 years

To all whom it may concern:

Be it known that I, LOUIS HARRY BUDD, a citizen of the United States and a resident of Malden, county of Middlesex and Commonwealth of Massachusetts, have invented a new, original, and ornamental Design for a Center Bar for Ophthalmic Mountings, of which the following is a specification, reference being had to the accom-

panying drawing, in which Fig. 1 is a front elevation of a center bar for ophthalmic mountings embodying my new design; and Fig. 2 is a plan view.

I claim:

The ornamental design for a center bar for ophthalmic mountings, substantially as shown.

LOUIS HARRY BUDD.
